UNITED STATES PATENT OFFICE.

WALTER F. HUNDEMER, OF ALAMEDA, CALIFORNIA.

DETACHABLE BOOSTER PUMP FOR GREASE GUNS.

Application filed June 1, 1925. Serial No. 33,999.

My invention is a detachable booster pump for a grease gun, adapted to be attached to any type of grease gun. The object being to provide a booster pump which may be attached to any type of grease gun to give high pressure to the grease being forced into a bearing and connection of any type.

As the ordinary grease guns on the market differ materially in shape, particularly the shape of the end of the gun to which the usual conduit is attached it is necessary to have the booster pump provided with an attachment or an adjustable connecting end so that it may be attached and fit tightly against the ordinary grease guns.

I provide several types of booster pumps one of which is built in a fixed size to be attached to the different types of grease guns. Another type has an adjustable connection or sleeve which, by being threaded in and out, may be adjusted to different types of grease guns. A third type has a removable sleeve which may be utilized in a position between the booster pump and the end of the grease gun. In this type it is necessary to have detachable sleeves which will be constructed to fit different types of grease guns now on the market.

The booster pump itself has a small bore cylinder preferably placed at right angles or across the grease gun with a small plunger and a long lever connected to the plunger so that high pressure may be developed in the booster pump. This forces the grease into a suitable conduit to the bearings to be greased.

My invention will be more readily understood from the following descriptions and drawings in which:—

40 Figure 1 is a side view, partly in sections, of a grease gun with the booster pump attachment in which the booster is made of a fixed size and adapted to suit only one type and shape of grease gun.

45 Figure 2 is a longitudinal section of a booster pump with a detachable sleeve adapted to fit various types of grease guns and having a spigot of hard metal. In this type the sleeve is a separate unit.

50 Figure 3 is a longitudinal section of a booster pump in which the sleeve is connected to the booster pump by a screw threaded connection whereby the sleeve may be adjustable.

Figure 4 is an end view of Figure 2 in the direction of the arrow 4.

55 Figure 5 is a modified form of booster pump in which the oil or grease is fed to a receptacle attached to the booster pump by some form of pumping for the grease.

60 Figure 6 is a modification of Figure 5 in which the grease pipe is directly connected with the booster pump conveying grease thereto through any suitable pumping system.

65 Referring particularly to Figure 1 the booster pump is designated generally by the numeral 1 and a grease gun by the numeral 2. The grease gun illustrated by 3 may be of any suitable shape and it is the purpose 70 of my invention to accommodate the attachment of grease gun to my booster pump by having a connection on the booster pump which will fit against the ends. 3 of the ordinary grease gun.

75 The booster pump has a pump body 4 having a longitudinal bore 5 which is usually placed at right angles to the axis of the grease gun. A plunger 6 operates in this bore being reciprocated by the lever 7 which is pivoted to a bracket 8 by means of pintles 9, pivot pin 10 connects the lever to the plunger. An inlet bore 11 leads into the bore of the booster pump and outlet 12 has a screw threaded fitting 13 to connect to a 80 grease conduit or pipe which conveys the grease to the bearing.

85 In Figure 1, the spigot 14 is shown in form integral with the metal of the body of the booster pump. The spigot is screw threaded 90 having a standard thread for the outlet of an ordinary grease gun. Collar 15 is formed integral with the body and at its outer end 16 bears against the surface 3 of a grease gun.

95 Referring to Figure 2 the body of the booster pump, the bore, and the plunger are the same as shown in Figure 1. The spigot however, is constructed with a removable screw threaded spigot element 17 being screw threaded into a socket 18 formed at the inlet of the booster pump. This spigot end has a nut section 19 by which it may be tightly screw threaded into the socket and connect with a lock-nut 20, so 100 that the spigot end 17 will be firmly held in the socket. This spigot end is made of a hard metal, usually of steel, whereas the

booster pump is usually made of brass, and the plunger 6 is made of a hard metal, such as steel. It has been found that in some cases the brass spigot is twisted off, or broken off connecting the different types of grease guns. With the removable spigot of hard metal this difficulty is overcome, as the hard metal will not break so readily and has a better connection to the heavy sock-
10 et 18.

The collar, or sleeve, 21, is entirely detachable and separable from the annular shoulder 22 of the booster pump the shoulder and sleeves being of proper size to
15 form a tight fit, and the end of the sleeves fitting tight against the end 23 of the booster pump. Different length sleeves will be supplied with a booster pump of the type shown in Figure 2 in order to accommodate grease guns having different shaped ends 3 or being of a different configuration.

In Figure 3 the booster pump is of substantially the same style or type as shown in Figure 2, the spigot being the same as disclosed therein. The detachable sleeves or collar 24, however, is screw threaded to the shoulder 25 and forms an adjustable connection. With this type of screw threaded
30 connection of the sleeve and the body of the booster pump, the sleeve can be rotated to fit it inward or outward, and thereby make a close fit with different types of grease guns.

35 The operation of my booster pump is as follows: The pump may be threaded onto any standard grease gun and if the gun is not self filling the handle or other device for feeding the grease from the gun will be
40 operated to fill the bore of the booster pump. It is necessary that the end of the grease gun and the booster pump form a tight connection and that the spigot is tightly threaded into the outlet of the grease gun,
45 and it is desirable to have an air tight connection; also the grease gun is used as one part of the lever being grasped in the hand while the lever 7 is operated to pump the booster pump. With some types of grease
50 guns the booster pump will automatically suck the grease from the grease gun and force it into the conduit through the outlet 13.

55 It will be readily seen that my booster pump may be modified considerably in detail and may be positioned in any suitable connection to the outlet end of a grease gun. The principal characteristics being that the booster pump and grease gun form
60 two hand holds which allows the operator to use considerable pressure to force the grease out of the booster pump into the bearing. However, different types of connections could be used between the booster pump and the grease gun in order to

make an adjustable connection which will fit any end of any type of grease gun on the market. In the several forms I have shown are illustrations of different connections I have found which are suitable to a great variety of grease guns.

In some types of high pressure booster pumps it is desirable to have a packing gland 6 having a packing 27 and a screw threaded packing gland sleeve nut 28 to hold the packing in place.

In Figures 1 to 4 inclusive I show a pumping arrangement for operating the plunger somewhat similar to that shown in application, Serial No. 556,393, filed April 25, 1922 for a grease gun by Albert T. Shere.

In Figures 5 and 6 I show a booster pump attachment having a single handed pumping arrangement as shown in patent to Nelson, No. 1,377,023. In this type the booster pump
85 may be held in one hand and for many of the bearings of an automobile or other machinery may be placed directly against the bearing inlet and the pump operated by one hand.

In Figure 5 the booster pump designated by the numeral 30 has a plunger operating in the body portion of the pump 31 in much the same manner as in Figures 1 to 4. A spring 32 is tensioned between the bushing 33 and a cross pin 34 so as to force the upper handle 35 upwardly so that the operator merely needs to squeeze the upper and lower handles 35 and 36, together to operate the pump. A tubular receptacle 37 is screw threaded into a collar 38 forming part of the pump and has a reducing coupling 39 to attach the pipe 40 which leads from a grease tank 41. In this type of construction the grease is shown as fed to the receptacle 37 by forcing compressed air through the pipe 100 42 into the grease tank.

The manner of feeding the grease to the receptacle 37 may be in accordance with any of the well known ways of pumping grease either by direct pumps or by the compressed air type as illustrated in the drawings.

In Figure 6 the booster pump is shown with the pipe 40 threaded directly onto a nipple 19 similar to that shown in Figures 2 and 3. When sufficient pressure is used to pump the oil or grease to maintain a steady supply this type is quite satisfactory and is a much lighter weight so that a person may readily hold the device and operate it with one hand.

120 It is manifest that the pumping system of supplying grease could be utilized with a booster pump as shown in Figures 1 to 4 and also that the type of booster pump shown in Figures 5 and 6 may be utilized with detachable grease guns in the manner similar to that shown in Figures 1 to 4. The connection shown in Figure 5 from the booster pump to the bearing indicates a jointed pipe construction similar to that described in my
125
130

application Serial No. 727,342, filed July 21, 1924, for high pressure grease conduit. Figure 6 is intended to indicate a direct attachment of the booster pump to the bearing to be lubricated.

Having described my invention, what I claim is:—

1. In combination, a booster pump comprising a cylinder having a plunger reciprocable therein, a lever operating the plunger, a link connection between the lever and the cylinder, a discharge port, a nipple extending from the peripheral body section of the cylinder, a grease gun having a tapered discharge end adapted to be screwed on the said nipple, a shoulder on the booster pump in concentric relation to the nipple and a
- 10
- 15

sleeve threaded thereon and adapted to be backed up against the tapered end of the cylinder for bracing the latter. 20

2. In combination, two conduits arranged at right angles to one another, a nipple extending radially from one of the conduits, a tapered end on the other conduit adapted to be threaded on the nipple and a centering 25 and bracing element threaded on the first conduit in concentric relation to the nipple and adapted to be backed against the tapered end of the second conduit for bracing the latter after the nipple thread has been engaged. 30

In testimony whereof I affix my signature.

WALTER F. HUNDEMER.
